UNITED STATES PATENT OFFICE.

EDWIN FIRTH AND JACOB CORNTHWAITE, OF TROY, NEW YORK.

ROLLS FOR PUNCHING AND CREEASING HORSESHOE-BLANKS.

SPECIFICATION forming part of Letters Patent No. 392,505, dated November 6, 1888.

Application filed May 10, 1888. Serial No. 273,351. (No model.)

To all whom it may concern:

Be it known that we, EDWIN FIRTH and JACOB CORNTHWAITE, citizens of the United States, residing at Troy, in the county of 5 Rensselaer and State of New York, have invented a new and useful Improvement in Rolls for Punching and Creasing Horseshoe-Blanks, of which the following is a specification.

Our invention relates to an improvement in 10 rolls for punching and creasing horseshoe-blanks; and it consists, first, in varying the diameter of the rolls proportionally to the thickness of the blanks to be punched to avoid breaking the punches; and, secondly, in the 15 peculiar construction and combination of devices, that will be more fully set forth herein-after, and particularly pointed out in the claims.

In the accompanying drawings, Figure 1 is 20 an end elevation of a pair of punching and creasing rolls embodying our improvements. Fig. 2 is an edge view of the same. Fig. 3 is a vertical sectional view of the same, taken on the line *x x* of Fig. 1. Fig. 4 is a sectional 25 view on line *y y* of Fig. 1.

The difficulty heretofore encountered in 30 punching horseshoe-blanks by means of rolls is that the punches speedily become broken and rendered useless, and this objection is of such moment as to have entirely prevented the 35 adoption of rolls for this purpose. We have discovered that by enlarging the diameters of the rolls proportionally with the thickness of the blanks to be punched and to the length of 40 the punches that the latter will be caused to operate in the blanks while the rolls are moving through a very small proportion of a revolution, so that the angles at which the punches are presented to the blanks while entering and 45 leaving the same will be so slight that the radii of the rolls will fall within the bases of the said punches, and hence the latter will not be subjected to injury or lateral strain, thereby rendering the punches sufficiently durable for

In carrying our invention into effect, A B 50 represent a pair of rolls of similar size and from two to six feet in diameter, according to the size of the blank to be operated upon. The perimeter of the lower roll is plane. The 55 perimeter of the upper roll is formed of two annular rings, C D, which are secured together

by transverse bolts E, and between the opposing sides of the said rings are formed oblong openings F. In the said openings are arranged 55 removable blocks G, the outer sides of which are curved to correspond with the radius of the roll and are provided with raised dies or flanges H, which are arranged longitudinally thereon, and are adapted to form the creases or 60 grooves in the horseshoe-blanks for the reception of the nail-heads. From the said dies or flanges project pointed punches I of suitable length and size to form the nail-holes in the horseshoe-blanks. In the ring D are trans- 65 verse threaded openings, which communicate with the openings F, and in the said openings are arranged clamping-screws K, which are adapted to bear against the sides of the blocks, so as to secure the same firmly in their seats. 70 The upper roll is further provided with a series of radial outwardly-extending adjusting-screws, L, which engage threaded openings in its rim and have their outer ends bearing against the inner sides of the blocks, the function of these screws being to adjust the said blocks radially toward and from the center of the rolls, as will be readily understood. In the periphery of the upper roll, at a suitable 75 distance apart, are annular grooves M, and the lower roll is provided with corresponding annular flanges, N, which are adapted to enter 80 said grooves.

The operation of our invention is as follows: The rolls are rotated in the direction indicated 85 by the arrows in Fig. 1, and the horseshoe-blank *a* is fed between the said rolls in the form of a bar of steel or iron of suitable length, breadth, and thickness, and heated to a suitable degree. As the rolls rotate, the faces of 90 the blocks engage the blank rod in succession, draw the same between the rolls, and cause the flanges or punching-ribs H of the blocks to make the grooves or creases in the blank, and the punches are also forced through the blank, 95 so as to make the nail-holes therein. Owing to the size of the rolls the punches are forced into and withdrawn from the blank while the rolls are moving through a comparatively small proportion of the revolution, and thereby 100 the punches are not subjected to injurious lateral strain, as before stated. We have found by practical tests that we are enabled to obtain the best results by varying the size of the

diameters of the rolls according to the thickness of the blank. A roll eighteen inches in diameter will operate successfully to punch holes in a piece of iron one-sixteenth of an inch in thickness, a roll thirty inches in diameter will punch a hole through a piece of iron one-eighth of an inch thick, a forty-inch roll will punch iron one-fourth of an inch thick, a five-foot roll will punch iron nine-sixteenths of an inch in thickness, a six-foot roll will punch iron three-fourths of an inch in thickness, and so on in about the same proportion.

It is essential to the perfect operation of the machine that the punches should be cooled in succession after acting on the hot blank to prevent them from losing their temper. In order to accomplish this result we arrange a reservoir or tank, R, over the upper roll, provide a brush, S, having wire bristles, which bear upon the punches on the upper side of the upper roll and have a perforated pipe, P, which communicates with the tank or reservoir and is adapted to feed the contents thereof to the bristles of the brush, and has a stop-cock, U, to regulate the supply of fluid to the brush. A suitable chemical solution is placed in the tank or reservoir and has the property of cooling the punches as the same are presented to the brush without crystallizing the steel in the punches and destroying the cohesion of the molecular particles thereof.

In order to prevent the points of the punches from being dulled by impinging against the periphery of the lower roll, we provide the latter with a dovetailed peripheral groove, a', in which is placed a copper rod, b, which entirely encircles the lower roll and has its ends connected. Before removing the lower roll from the lathe on which it is turned and finished a spinning-tool is caused to bear against the said copper rod while the roll is in rotation, the effect of the said spinning-tool being to mash and spread the copper rod down into the groove and cause it to fit snugly therein.

When the machine is in operation, the copper band on the lower roll receives the impact of the points of the punches as the same pass through the blanks, thereby preventing said punches from being dulled.

We do not limit ourselves to the use of copper for this purpose, as other soft metals may be used in lieu thereof.

Having thus described our invention, we claim—

1. The rolls for punching horseshoe-blanks, the diameters of the said rolls varying according to the thickness of the blanks in about the proportions described.

2. The rolls having the punches for making holes in horseshoe-blanks, the diameter of the rolls being such that the same will move through only a small proportion of a revolution while each punch is operating on the blank, whereby lateral strain on the punches is avoided, substantially as described.

3. The combination, with the rolls, of the blocks secured to one of the rolls and remov-

able therefrom, said blocks having the raised flanges or dies H, substantially as described.

4. The combination, with the rolls, of the blocks secured to and detachable from one of the rolls, said blocks having the punches I, substantially as described.

5. The combination, with the rolls, of the blocks secured to and detachable from one of the rolls, said blocks having the raised flanges or dies H, and the punches I, projecting therefrom, substantially as described.

6. The combination of the roll A, having the peripheral recesses, with the punching blocks or dies arranged in said recesses, and the clamping-screws to secure the said punches and dies in position, substantially as described.

7. The combination of the roll A, having the peripheral recesses, the punching-blocks arranged in the said recesses, and the screws to move said blocks radially therein, substantially as described.

8. The combination, in a roller for the purpose set forth, of the rings C D, bolted together and having the oblong openings F formed in their opposing sides, substantially as described.

9. The combination of the roll A, having the annular grooves M and provided with the punches, with the roll B, having the annular tongues or flanges N, engaging the grooves M, substantially as described.

10. The combination of the rolls carrying the punches, the brush arranged above the roller and bearing on the periphery thereof, and the perforated pipe to supply cooling-fluid to the brush, for the purpose set forth, substantially as described.

11. The combination, with the roller, of the brush bearing against the upper roll, the reservoir or tank, and the perforated pipe communicating therewith and with the brush to supply fluid to the latter, said pipe having the regulating-valve or stop-cock, substantially as described.

12. The combination, with the roll having the peripheral punches, of the roll having the soft-metal peripheral band to receive the impact of the punches, substantially as described.

13. The lower roll having the peripheral groove and the soft-metal band in said groove, for the purpose set forth, substantially as described.

14. The lower roll having the dovetailed peripheral groove and the soft-metal band fitted in said groove, substantially as described.

In testimony that we claim the foregoing as our own we have hereto affixed our signatures in presence of two witnesses.

EDWIN FIRTH.
JACOB CORNTHWAITE.
